COLD CATHODE TUBE

James E. McLinden, Jr., Rego Park, N. Y., assignor to Bendix Aviation Corporation, Teterboro, N. J., a corporation of Delaware

Application November 10, 1947, Serial No. 785,051

13 Claims. (Cl. 313—193)

1

This invention relates to cold cathode tubes in which materials of a low work function are used in forming the cathode.

An object of my present invention is to provide a tube having a cathode of low work function which will furnish high peak currents of short duration at moderate repetition frequencies from a low frequency, low tension source of supply suitable for high frequency ignition systems, switching circuits, excitors, and pulsers.

Another object of my invention is to provide a tube having a cathode of a low work function material, with a sputtering inhibitor by which arcing and shorts occurring in the tube are materially reduced.

A further object of this invention is to provide a tube having a low work function material as a cathode with increased spacings between the elements thereof to prevent shorts and premature arcing due to sputtered cathode material.

Still another object of the invention is to provide a tube of the character indicated in which the dissipation of the heat generated by the cathode is greatly improved, reducing thereby the evaporation of the active cathode material.

Still a further object of my invention is to provide a highly improved cold cathode tube of the character indicated which shall consist of few and simple parts readily assembled in mass production, the resulting assembly being mechanically rigid and free of vibrations; which shall be positive in its action and have a comparatively long life, and which shall have a large variety of applications and yet be practical and efficient to a high degree in use.

Other objects of my invention will in part be obvious, and in part hereinafter pointed out.

The improved cold cathode tube provided by me comprises a cathode of a low work function, a control grid and an anode hermetically sealed in an envelope filled with helium. The cathode of the present invention is made by compressing powdered cesium chloride and aluminum with nickel filings into a pill of desired form and mounting the same in a cathode cup. The cathode cup engages the glass envelope enclosing the tube elements to facilitate dissipation of the heat generated in the cathode pill.

Metallic cesium is the active part of the cathode thus formed. Since metallic cesium has an extremely low work function which permits electrons to be emitted at low temperatures, a cesium compound is used to inhibit the vaporization of the cesium. While I have indicated cesium

2

chloride as the preferred compound in the manufacture of the cathodes, it will be readily appreciated that other low work function materials may be used, such as the alkali metals, the earth alkali metals, or the rare earth metals. Similarly, other metal powders may be used in place of aluminum powder indicated as being preferred.

The control grid of my tube is made of carbon preferably in the form of graphite, cylindrical in shape and encompassing a tungsten anode. The grid is made of carbon so that any sputtered cesium will not readily adhere thereto.

Upon application of a proper voltage to the control grid, an initial glow discharge will take place between the grid and the normally grounded cathode. When the current reaches a sufficient density at the surface of the cold cathode, a cathode spot is formed. The action of the cathode spot permits the cesium chloride to decompose, aluminum taking the place of the cesium to form aluminum chloride. A thin layer of cesium is thus formed on the surface of the cathode pill which will cause an arc discharge between the cathode and the anode.

In an arc discharge of the character described, the sputtering of the cesium has been a problem in previous tubes of this character. The carbon grid provided does reduce the problem of sputtered cesium in that cesium will not readily adhere thereto. There is therefore no emission from the grid to the anode due to the sputtered cesium to cause premature arcing between these elements. By increasing the spacings of the tube elements I also reduce the inherent tendencies of premature arcings.

Nickel filings are added to the cathode pill to reduce the sputtering of the active material. The nickel filings in the pill reduce the cathode surface resistance and cause the arcs to strike the exposed nickel filing particles rather than the active material itself. The large bursts of current will not erupt the active material, the arc taking place between the nickel filings and the anode.

By providing an external cathode cap for my tube, I increase the rate of heat dissipation of the heat developed by the cathode pill. The evaporation of the cesium is thus materially reduced, reducing the inherent sputtering and increasing thereby the active life of the tube. A further advantage gained by the use of my external cathode cap is the prevention of cesium deposits on the cathode support. Arcs to the anode from the cathode support are thus prevented, as was heretofore prevalent.

Accordingly, in the accompanying drawings I have shown one of the various possible illustrative embodiments of my invention, of which

Fig. 1 is a vertical cross-sectional view with portions thereof in elevation, of a cold cathode tube embodying my invention and taken approximately along the line 1—1 of Fig. 2.

Fig. 2 is a cross-section view taken along the line 2—2 of Fig. 1, while

Fig. 3 is a cross-sectional view taken along line 3—3 of Fig. 1.

Referring now to the drawings, the numeral 10 designates a cold cathode tube embodying my invention. The tube comprises a glass sleeve 11 having fixed therein and made integral with the bottom edge thereof, a second glass sleeve 12 extending upwardly within the tube 11 and terminating in a three-sided glass press 13 (Fig. 3). Supported on, and fixed to the upper face of the glass press is a ceramic insulator 14 formed with coextensive and concentric openings 15, 16 and 17 of different diameters, openings 15 and 16 forming an annular shoulder 18 for the purposes hereinafter apparent. The insulator 14 is further provided with a series of radial slots 19 cut into the side of the insulator and registering with the opening 17, the pie-shaped pillars 20 supporting the upper portion 21 of the insulator. To align the tube elements hereinafter described, a series of longitudinal openings 22 and 23 are provided in the ceramic insulator 14 and in the glass press 13, respectively (Figs. 1 and 3). A pin 24 inserted in a pair of openings 22, 23 will align the insulator and the glass press.

Cut into the top surface of portion 21 is an annular groove 25. Supported in said groove in an inverted position and facing inwardly of the envelope is a cathode cup 26 preferably made of nickel. Substantially the entire outer surface of the cathode cup engages a cathode cup 27, preferably of kovar; the lower edge of the cap being sealed to the glass sleeve 11 to form a hermetically sealed tube. The sealed tube is filled with an inert gas, preferably helium.

Fixed within the cathode cup 26 is a cathode pill 30 forming the actual cathode for the tube 10. The pill is made by compressing cesium chloride, aluminum powder and nickel filings into the desired form. The pill is held within the cup by a wire mesh screen 31, preferably made of nickel.

A carbon grid 32, cylindrical in form is fixed within the openings 15 and 16 of the ceramic insulator. The grid 32 is formed with an annular shoulder 33 on its exterior and a tapered bore 34 in its interior. The grid shoulder 33 abuts the shoulder 18 of the insulator to space the grid properly within the insulator so that the grid extends slightly above the upper end of opening 16. The tapered bore 34 of the grid forms a partial enclosure for a rod-like tungsten anode 35. A glass bead 36 about the lower end of the anode serves to reduce the possibility of shorts or arcing.

Electrical connections are provided for the grid 32 and the anode 35 through the glass press 13 by two lead-in wires 38 and 39. The grid 32 is connected to the lead-in wire 38 by a contactor 40 fixed into the glass press and fitting within an opening 41 formed in the insulator 14. The cathode 30 of the tube is connected by way of the cup and cap into the electrical circuit.

With proper voltage applied to the grid 32, a glow discharge will take place between the grid and the cathode 30. The decomposition of the cesium chloride of the cathode will form a cath-

ode spot on the pill which will emit electrons to form a low resistance path from the cathode to the anode 35. An arc discharge will then take place between anode and cathode, the arc striking the nickel filings of the cathode pill rather than the active material of the pill. It was found that the nickel screen 31 retaining the cathode pill within the cup 26 did not prevent the pitting of the pill when the arc was struck. The nickel filings however compressed in with the cesium chloride and aluminum did prevent the objectionable pitting heretofore found in available cold cathode tubes.

The heat developed in the cathode is quickly dissipated by the external cathode cap. Evaporation of the active material is reduced adding materially to the life of the tube.

It should be noted that sputtering of the active material is inherent in tubes of this character. The arcing and shorts resulting from sputtered material has been materially reduced by the use of the nickel filings in the pill and by increasing the spacings of the tube elements.

In the construction described, the ceramic insulator 14 has been provided with a series of slots 19 registering with the opening 17 between the cathode and the grid. From Fig. 2 it will be apparent that only a knife edge of the pillars 20 lies in the path between the cathode and anode. The minute particles of active material will therefore pass out of the slots 19 into the space between the insulator and the envelope. The cesium particles will adhere to the exterior of the insulator and to the faces of the wedges 20, rather than to the knife edges. With the sputtered material deposited at considerable distance from the tube elements, the voltages applied to the grid or anode will be insufficient to bridge the extra distance to cause the shorts and arcing heretofore had in tubes of this type.

A further advantage in the construction described is the solid support provided for the insulator 14 by the three-way glass press 13. The grid 32 nested within the insulator and the extremely short anode 35 fixed into the press 13 prevents fracture and displacement of these elements by any vibrations acting upon the tube. The cathode 30 is also rigidly mounted within the tube envelope and is supported by the ceramic insulator.

There is thus provided a highly improved cold cathode tube having a long life in which sputtering of the active materials has been materially reduced, in which shorts and premature arcing is virtually eliminated, in which evaporation of the active material has been reduced by increasing the heat dissipation of the tube and in which the tube elements are mechanically rigid.

As various possible embodiments may be made of the above invention, and as various changes might be made in the embodiment above set forth, it is to be understood that all matter herein set forth, or shown in the accompanying drawings, is to be interpreted as illustrative and not in a limiting sense.

Having thus described my invention, I claim as new and desire to secure by Letters Patent:

1. A gaseous discharge tube comprising an envelope, a cylindrical insulator fixed within said envelope, a cylindrical control grid of carbon nested within said insulator, an inverted cup supported by said insulator and spaced from said grid, a plurality of openings in said insulator between said cup and said grid, a pill containing a material of low work function in said cup form-

ing the cathode of the tube, nickel particles in said pill, a wire mesh screen to retain said pill in said cup, a tungsten anode fixed within said insulator, and an inert gas filling said envelope.

2. A gaseous discharge tube comprising an envelope, a cylindrical insulator within said envelope, a cylindrical carbon grid nested within said insulator, an anode encompassed by said grid and fixed within said insulator, a cup supported by said insulator and spaced from said grid and anode, a pill containing a material of low work function within said cup and forming the cathode of the tube, nickel particles in said pill, and an inert gas within said envelope.

3. A gaseous discharge tube comprising an envelope, a cylindrical insulator mounted within said envelope, a carbon grid fixed to said insulator, a cup supported by said insulator and spaced from, and facing said grid, a pill containing a material of low work function within said cup, nickel particles within said pill, an anode fixed within said insulator in proximity to said grid, and an inert gas filling said envelope.

4. A gaseous discharge tube comprising an envelope, a cylindrical insulator fixed within said envelope, a carbon grid fixed to said insulator, a cup supported by said insulator and engaging said envelope and spaced from said grid, a plurality of vents in said insulator between said cup and said grid, a pill containing a material of low work function within said cup, and an anode in proximity to said grid fixed within said insulator.

5. A gaseous discharge tube comprising an envelope, a cylindrical insulator therein having three coextensive openings of different diameters, a cylindrical grid nested within the first two of the openings of said insulator, a cup supported by said insulator and closing the third of said openings, a plurality of transverse slots in said insulator between said cup and said grid registering with the third of said openings in said insulator, a pill containing a material of low work function in said cup forming the cathode of the tube, an anode fixed within the first of said openings in said insulator and encompassed by said grid, and an inert gas in said envelope.

6. A gaseous discharge tube comprising an envelope, a cylindrical insulator fixed within said envelope and having at least two coextensive openings of different diameters, a grid fixed in the smaller of said openings and extending into the larger of said openings, a cup supported by said insulator and closing the larger of said openings, a plurality of transverse vents in said insulator between said cup and said grid registering with the larger of said openings in said insulator, a pill containing a material of low work function forming the cathode of the tube, an anode within the smaller opening of said insulator, and an inert gas filling said envelope.

7. A gaseous discharge tube comprising an envelope, a cylindrical insulator fixed within said envelope and having at least two coextensive openings of different diameters, a cylindrical carbon grid fixed in the smaller of said openings and extending into the larger of said openings, a cup supported by said insulator and closing the larger of said openings, a plurality of transverse vents in said insulator between said cup

and said grid registering with the larger of said openings in said insulator, a pill containing a material of low work function forming the cathode of the tube, nickel particles in said pill, an anode of tungsten within the smaller opening of said insulator, and an inert gas filling said envelope.

8. A gaseous discharge tube comprising an insulator fixed within the tube envelope and having at least two coextensive bores therein of different diameters, a cathode holder supported on said insulator and closing the end of the larger bore therein, a grid fixed within the smaller of said bores, a plurality of transverse vents in said insulator registering with the larger bore, and an anode in proximity to said grid and within the smaller bore of said insulator.

9. A gaseous discharge tube comprising an insulator fixed within the tube envelope and having at least two coextensive bores of different diameters, a cathode holder supported on said insulator and closing the end of the larger bore, an annular grid fixed within the smaller of said bores, a plurality of transverse vents in said insulator registering with the larger bore, and an anode fixed concentrically with said grid within said smaller bore.

10. A discharge tube including an envelope, insulator means fixed within said envelope, a control grid and an anode supported by said insulator means, and a cathode of low work function having a cup supported by said insulator means and engaging a substantial area of said envelopes to facilitate dissipation of heat generated in the cathode.

11. A discharge tube including an envelope, a cathode of low work function having a cup mounted within said envelope and having an open end facing inwardly of the envelope and substantially the entire outer surface of the cup engaging the walls of said envelope to facilitate dissipation of heat generated in the cathode.

12. In a discharge tube, a cathode containing a compound including an element of low work function, a substance to displace the element of low work function from said compound during discharge, and free nickel particles to provide points at which the arc of the discharge occurs.

13. In a discharge tube, a cathode in pill form containing a cesium compound, powdered aluminum for reacting chemically with said compound during discharge and displacing the cesium therefrom, and nickel filings to provide points at which the arc of the discharge occurs.
